UNITED STATES PATENT OFFICE.

JAMES J. FURLONG, OF TACOMA, WASHINGTON.

EYE-SHIELD.

1,274,257.

Specification of Letters Patent. Patented July 30, 1918.

Application filed January 28, 1918. Serial No. 213,396.

To all whom it may concern:

Be it known that I, JAMES J. FURLONG, a citizen of the U. S. of A., residing at Tacoma, in the county of Pierce and State of 5 Washington, have invented new and useful Improvements in Eye-Shields, of which the following is a specification.

This invention relates to eye shields or eye protectors and it has for its object to produce a simple device of improved construction which will effectively protect the eyes against excessive sunlight or artificial light as well as against the blinding effects of snow and the like whereby the sunlight is 15 vividly reflected.

A further object of the invention is to produce a simple and effective device of the character described which may be usefully employed by the drivers of motor vehicles 20 and the like for the purpose of protecting the eyes not only without impairing the vision but actually improving the vision by limiting the field thereof.

A further object of the invention is to 25 produce an eye protector which will be made mainly of material which will be non-injurious to the face by contact therewith in any extremes of temperature.

With these and other ends in view which 30 will readily appear as the nature of the invention is better understood, the same consists in the improved construction, arrangement and combination of parts which will be hereinafter fully described and particularly pointed out in the claims.

In the accompanying drawing has been illustrated a simple and preferred form of the invention, it being, however, understood that no limitation is necessarily made to 40 the precise structural details therein exhibited, but that changes, alterations and modifications within the scope of the claims may be resorted to when desired.

In the drawing,—

45 Figure 1 is a front view showing a pair of the improved eye protectors.

Fig. 2 is a side view showing the same applied in position for operation.

Fig. 3 is a horizontal sectional view showing the protectors detached.

Fig. 4 is a vertical sectional detail view taken through the center of one of the protectors.

Corresponding parts in the several figures 55 are denoted by like characters of reference.

The improved eye protecting device con-

sists of a pair of convexo-concave disks 15 of approximately circular shape, each having a flat face engaging flange 16. Each disk is provided at the outer portion thereof with a straight substantially vertical edge 60 17. Each disk is also provided with an obliquely disposed straight edge portion 18 extending from the lower to the inner edge thereof, said oblique edge portion being at 65 an angle of approximately 45 degrees with respect to the straight edge portion 17. Each of the disks 15 is also provided with a horizontally disposed narrow slit 19 which may be of any desired length, said slit communicating with a circular aperture 20 which latter should be located approximately in alignment with the pupil of the eye when the protector is adjusted in position for operation. 75

Hingedly connected with the disk 15 adjacent to the straight vertical edge portion thereof, as by means of loops or links 21, is a guard piece 22, a rubber or other elastic cord 23 being terminally connected with said guard pieces to pass behind the head of the wearer for the purpose of supporting the protecting device in position on the face. The obliquely disposed straight edge portions 18 will adapt the shields or disks to 80 the contour of the face by engagement with the bridge of the nose. Ear engaging bows 24 of ordinary construction are also connected with the guard pieces 22. These bows may be utilized independently of the 85 elastic cord 23, but the latter is preferably used in connection with the bows for the purpose of relieving the pressure of the latter against the ears of the wearer, thus affording additional security for maintaining 90 the device in position. 95

I am aware that various materials such as metal, glass, celluloid and the like have been used in the manufacture of eye protectors such as goggles which are commonly 100 used by the drivers of motor vehicles. I have discovered however, that nearly all materials heretofore employed have been more or less defective on account of the injurious action on the skin of the wearer and also 105 for the reason that in extreme conditions of temperature the skin would be injuriously affected by contact with the materials of which such goggles or protectors have been constructed. I have discovered that there is 110 one material which is particularly adapted for use in this connection, said material be-

ing horn which as is well known is practically identical with the material composing the human hair and nails. Horn is not affected by extremes of temperature, and the contact thereof with the human skin is absolutely uninjurious under any conditions. The disks constituting my improved protectors will therefore be made of this material or of any artificially produced material which may be found identical therewith in composition and in actual results.

In order that a person meeting another person wearing the improved shield may not be confronted with the unpleasant spectacle of what would appear to be a person without eyes, it is intended that the representation of a human eye shall be painted on each of the disks 15 as indicated at 30 in Figs. 1 and 2.

The improved eye protectors herein described may be worn without inconvenience and without impairing the vision, ample field vision being provided by the elongated slots 19 and the apertures 20. Blinding of

the wearer by excessive light or by light reflected from snow and the like will thus be avoided. The disks constituting the improved eye protectors may be connected together by a bridge piece 25 or in any approved manner.

What is claimed, is:—

1. An eye protector comprising a pair of connected concavo-convex disks formed of translucent material and provided centrally with vision permitting openings, and said disks having the representation of human eyes painted externally thereupon.

2. An eye protector comprising a pair of connected disks, each being concavo-convex in form and provided with vision permitting openings, a peripherally extending flat face engaging flange on each disk formed to accommodate the wearer's nose and having its outer portion cut away on a vertical line, and a side guard member hinged upon said vertical edge.

In testimony whereof I affix my signature.
JAMES J. FURLONG.
